UNITED STATES PATENT OFFICE.

HOWARD NEWTON SHRIVER, OF BEACHMONT, MASSACHUSETTS.

CIGAR TUCK-CUTTER AND PERFORATOR.

1,252,044.

Specification of Letters Patent. Patented Jan. 1, 1918.

Application filed September 18, 1916. Serial No. 120,738.

To all whom it may concern:

Be it known that I, HOWARD NEWTON SHRIVER, a citizen of the United States, residing at Beachmont, in the county of Suffolk and State of Massachusetts, have invented new and useful Improvements in Cigar Tuck-Cutters and Perforators, of which the following is a specification.

Broadly stated this invention comprehends the provision of a machine wherein the small end of a cigar is simultaneously perforated with the trimming or cutting of the tuck or large end of the cigar, thereby eliminating the necessity of the smoker biting off the small end thereof, which frequently results in the unwinding of the wrapper of the cigar.

The nature and advantages of the invention will be readily apparent as the following detail description is read in connection with the accompanying drawings, the invention residing in the construction, combination and arrangement of parts as claimed.

In the drawings forming part of this specification like numerals of reference indicate similar parts in the several views and wherein:

Fig. 1 is a side elevation partly in section showing the normal position of the parts.

Fig. 2 is a similar view showing the manner of perforating the small end of the cigar.

Fig. 3 is an enlarged end view showing the movable cutting blade in normal position.

Fig. 4 is a similar view showing the cutting blade in operative position.

Fig. 5 is a horizontal sectional view showing the normal position of the bell crank lever.

Fig. 6 is a similar view showing the active position of the lever.

Fig. 7 is a front end elevation.

Referring more particularly to the drawings in detail 10 indicates the base of the machine which is preferably of elongated rectangular formation, and which may be constructed from any suitable material.

The upper surface of the base is provided with a longitudinally extending groove 11

which extends to one end of the base, and is adapted to receive the cigar to be treated. Secured to this end of the base is a fixed blade 12 with which cooperates a relatively 55 movable cutter blade 13 pivoted upon the end of the base, and normally held elevated by means of the spring 14, which latter has one limb secured to the fixed blade 12 and its opposite limb connected with the movable blade 13. The movable blade 13 is provided with an elongated slot 15 for the reception of a guide pin 16. The respective blades 12 and 13 are each provided with a semicircular cut-out portion 18 between 60 which the large end or tuck of the cigar projects when the latter is arranged within the groove 11. The movable blade 13 is provided with a curved tail portion 19 which projects inwardly and operates within an 65 enlarged transverse recess or pocket 20 opening at that end of the base upon which the cutter blade is pivoted.

Mounted upon the base 10 at the opposite end thereof is a sleeve 21 which may be of 70 any suitable cross sectional configuration and of any desired dimensions, the sleeve being partly embedded within the upper surface of the base as shown. The innermost end of the sleeve has fitted therein a 75 plug 22 which is arranged immediately adjacent the inner extremity of the groove 11 and provided with a conical shaped opening 23 for the reception of the small end of the cigar when the same is positioned upon the 80 base 10. The plug 22 has a plurality of restricted openings or bores 24 communicating with the conical shaped opening 23, and also opening at the opposite end of the plug 22. The bores 24 receive the pointed terminals of needles 25, the opposite ends of which are secured to the plunger 26, which latter is slidably fitted within the sleeve 21. The plunger is carried by the extremity of an elbow 27 on the rod 28 which latter is 85 mounted for longitudinal movement within a bore 29 formed in the base 10 and communicating with the recess or pocket 20. 90

Pivoted for horizontal swinging movement within the pocket or recess 20 is a bell 100 crank lever 30 having the terminal of one of its branches arranged within an elon-

gated slot 31 provided in the adjacent end of the rod 28, while the terminal of the other branch of said lever is reduced and loosely fitted within an enlarged opening 32 in the 5 tail portion 19 of the movable blade 13. The opening 32 must be sufficiently large to provide for a certain play between the cutting blade 13 and the bell crank lever 30, as the tail portion of the blade moves in an arc of 10 a circle transversely of the base, while the connected end of the bell crank lever moves in an arc of a circle at right angles to the movement of the tail portion 19.

In practice, a cigar is positioned within 15 the groove 11 with its small end arranged within the conical opening 23 of the plug 22, and its large end or tuck projecting beyond the base within the cut-out portions 18 of the respective cutting elements. The 20 cutting blade 13 being normally elevated, is depressed against the tension of the spring 14 for the purpose of cutting or trimming the tuck of the cigar. Upon movement of the lever in this direction the tail portion 25 18 thereof moves outwardly of the recess or pocket 20 in an arc of a circle transversely of the base 10, and by reason of the arrangement of the bell crank lever 30 and its connection with the cutting blade 13, the lever 30 30 is simultaneously moved upon its pivot to adjust the rod 28 longitudinally of the base, or in other words retract the rod 28 within its bore 29. With this operation the plunger 26 is moved within the sleeve 21 in 35 the direction of the plug 22, thereby forcing the needles 25 within the small end of the cigar, perforating the latter in the direction of its length. When pressure is removed from the cutting blade 13, the spring 14 40 functions to elevate the blade, during which movement of the latter the component parts of the machine are returned to normal position.

While it is believed that from the foregoing description the nature and advantages 45 of the invention are apparent, I desire to have it understood that what is herein shown is merely illustrative of the preferred embodiment of the invention, and that such 50 changes in the construction and arrangement of parts may be resorted to when desired as fall within the scope of what is claimed.

What is claimed is:—

55 1. In a machine of the class described, a base having a recess opening at one side and end thereof, a bell crank lever pivoted upon the base for horizontal movement and arranged within said recess, a rod arranged 60 longitudinally of the base and having an opening at one end for the reception of the adjacent extremity of said lever, whereby said rod is reciprocated upon movement of the lever, means for trimming the tucks of

cigars, said means including a fixed blade 65 and a movable blade pivoted upon the base, said movable blade being directly connected with the opposite end of said lever for controlling the movements of the latter, and means on the opposite end of said rod for 70 perforating the small end of the cigar in the direction of its length simultaneously with the trimming of the tuck thereof.

2. In a machine of the class described, a base having an enlarged recess opening at 75 one side and end thereof, and a longitudinally disposed bore communicating with said recess and opening at the opposite end of the base, a rod arranged to reciprocate in said bore, a bell crank lever pivoted upon the base for horizontal movement and operating within said recess, one end of said lever being connected with the adjacent end of said rod to operate the latter upon movement of said lever, means for trimming the 80 tucks of cigars, said means including a fixed blade and a movable blade pivoted upon the base, said movable blade being directly connected to the opposite end of said lever for controlling the movements thereof, and means on the opposite end of said rod for 85 perforating the small end of the cigar in the direction of its length simultaneously with the trimming of the tuck thereof.

3. In a machine of the class described, a 95 base, means for trimming the tucks of cigars, said means including a fixed blade and a movable blade pivoted upon the base, a rod movable longitudinally of the base, a bell crank lever pivoted upon the base for horizontal movement and connected with one end of the rod to operate the latter, said movable blade being directly connected with the adjacent extremity of said lever, a sleeve 100 mounted upon the base, a block fitted in one end of the sleeve and having a conical shaped opening and restricted bores communicating with said opening, a plunger arranged to reciprocate in said sleeve, said plunger being carried by the opposite extremity of said rod, and a plurality of needles 105 projecting from said plunger and operating in said bores of the block to perforate the small end of the cigar in the direction of its length simultaneously with the trimming 110 of the tuck thereof.

4. In a machine of the class described, a base having an enlarged transverse recess opening at one side and end thereof, and a longitudinally extending bore communicating with the recess and opening at the opposite end of the base, a bell crank lever pivoted within said recess for horizontal movement, means for trimming the tucks of cigars, said means including a fixed blade 120 and a movable blade pivoted upon the base, said movable blade being directly connected with the adjacent end of said lever for 125

trolling the movements thereof, a rod movable longitudinally of the base and arranged within said bore, said rod being connected with the opposite end of the lever, an elbow 5 formed on one end of the rod and terminating above the base, and means carried by said elbow for perforating the small end of

the cigar in a direction of its length simultaneously with the trimming of the tuck thereof.

10

In testimony whereof I affix my signature.

HOWARD NEWTON SHRIVER.
